Attorney

UNITED STATES PATENT OFFICE.

WILFRED A. HARE, OF DETROIT, MICHIGAN.

AUTOMATIC STOKER.

Application filed July 14, 1919. Serial No. 310,794.

To all whom it may concern:

Be it known that I, WILFRED A. HARE, a subject of the King of England, residing at Detroit, in the county of Wayne and State 5 of Michigan, have invented certain new and useful Improvements in Automatic Stokers, of which the following is a specification, reference being had therein to the accompanying drawings.

10 In forced draft furnaces where the air for maintaining combustion is forced upwardly between the grate bars, it is common practice to provide an air tight chamber beneath the bars into which the air is introduced in various ways, preferably through hollow grate bars to cool the bars and to heat the air. To provide a furnace with such a chamber complicates the structure and its installation, and leakage causes 15 inefficient operation.

Further, the air under pressure in such a chamber will travel in paths of least resistance and therefore it is difficult to maintain an even distribution of air over the entire 20 grate surface. The present invention contemplates the overcoming of these difficulties by confining the air within a plurality of passages directly below the grate surface upon which the fuel is burned, and delivering 25 it directly from these several passages to the several spaces between the hollow bars providing such surface, thus securing an even distribution of air to the grate surface and obviating the necessity for installing 30 and maintaining an air-tight chamber beneath the grate comprising the several hollow grate bars. A further object of the invention is to provide a suitable ash grate 35 which will catch all unburned fuel and to 40 which air is supplied for burning such fuel, said grate being arranged to facilitate the removal of ash and clinkers, and further, to provide certain other new and useful features in the construction, arrangement and 45 combination of furnace parts, all as herein-after more fully described and shown in the accompanying drawing.

With these and other ends in view, the invention consists in the matters hereinafter 50 set forth, and shown in the drawing in which—

Figure 1 is a vertical section through a portion of a furnace illustrative of the in-

vention, and showing one side of a hollow 55 grate bar partly broken away and in section as shown at the lower side of Fig. 3;

Fig. 2 is a similar view illustrating the movements of the grate bars;

Fig. 3 a plan view of several grate bars 60 with portions broken away and in section to show the construction; and

Fig. 4 is a cross-section of a plurality of 65 grate bars substantially upon the line IV—IV of Fig. 3.

To illustrate an application of the invention to a furnace, the same is shown as applied to an automatic stoker having a retort 1 into which the fuel is fed in the usual manner (not shown), and wind box 2 beneath the retort for supplying air under pressure to maintain combustion. Supported upon the upper edges of the wind box and retort and spanning the space between 70 said edges at one or both sides of the retort, 75 is a suitably constructed hollow twyer or twyers 3, and extending laterally from one or both sides of the wind box are hollow grate bars 4 and 5 forming the grate upon which the fuel is burned with the upper ends of said bars supported upon the wind box and in communication with said box through the twyer. A suitable channel beam 6 forms a support for the lower ends of the grate bars and spaced from said lower ends is a furnace side wall 7, the space between said 80 wall and grate being closed by an ash grate 8 which rests at one end within a clean-out 85 opening 9 in said wall closed by a suitable door or doors 10, the inner end of said ash 90 grate being pivotally attached at 11 to the ends of the movable grate bars 5, to move therewith.

The fixed (4) and movable (5) grate bars are arranged in alternate relation to make 95 up the grate upon which the fuel is burned, and these movable bars are each provided with the usual socket 12 at its lower end to receive a supporting rib 13 on a rock shaft 14 which is mounted in bearings 15 on the beam 6. This shaft is rocked in any suitable manner, as by an arm 16 on the shaft and an operating rod 17 connected to the lower end of the arm and receiving motion from other moving parts (not shown) of the mechanism. Upon rocking the shaft 14, 100 the grate bars 5 are raised slightly at their 105

lower ends and moved endwise in the usual manner to agitate the fuel and feed it down upon the grate toward the ash grate 8 which receives the ash and clinker, and in turn 5 discharges the same into the clean-out opening 9. The pivotal connection of the ash grate to the grate bars 5 permits of the free rising and falling movement thereof and as the outer end of the ash grate rests by 10 gravity upon the bottom wall of the opening 9, free longitudinal movement is permitted, said end of said ash grate sliding freely within the opening to feed ash and clinker into it. These products of combustion 15 may therefore be readily cleaned out at any time by opening the door 10 and without interfering with the continuous operation of the furnace, and the entire grate surface and operation of the furnace may 20 be observed, by opening said door.

The lower ends of the fixed grate bars are supported in the usual manner by a suitable rib 18 carried by the beam 6 to engage a notch in the lower side of each bar, and at 25 their upper ends, all of the grate bars are supported upon a shelf or ledge 19 projecting laterally from the side of the wind box 2.

Each grate bar is formed with a plurality 30 of longitudinal air passages, there being two air inlet passages 20 directly below the upper surface of each bar upon which the fuel is burned, and these passages open through the upper end of the bar directly 35 into the hollow twyer 3 to receive air passing upward therethrough from the wind box. Near the lower ends of the bars, an opening 21 is provided in the bottom of each passage 20, through which openings the air 40 passes into channels 22 directly below the passages 20. These return or outlet channels 22 are formed in adjacent sides of adjacent bars, that is, the channel in one side of one bar confronts the channel in the adjacent side of the next bar and these confronting channels together form a return or 45 outlet duct in adjacent bars, so that the slots or openings 23 in the grate surface between adjacent bars, are in direct communication 50 with these channels 22 which together form the outlet or return ducts, the air in said ducts being free to pass upwardly and out through the several slots between the bars throughout their length to maintain combustion upon the grate. The lower side 55 edges of the several bars are formed to fit tightly together, they being flanged downwardly as at 24 to provide edge contact faces which will prevent the escape of air 60 between said edges from the return ducts formed by the channels 22. The upper or twyer ends of the several return ducts are closed by an end wall 25 but in the movable bars 5, slots or openings 26 are provided in 65 the bottom wall 27 of each channel 22 ad-

jacent said end wall 25 to permit the escape of a small amount of air downwardly into the space below the grate, said openings 26 being so arranged that when these movable grate bars are moved endwise toward the 70 retort and twyer, as shown in Fig. 1, the openings will be closed by the ledge or shelf 19 upon which said ends of the bars rest and slide. When these movable grate bars are moved longitudinally to the opposite end of their stroke as shown in Fig. 2, these openings 26 will be opened and permit air to escape into the space 28 below the grate, and as this space is in free communication with the space or chamber 29 below the ash grate 8, the air escaping intermittently through the openings 26 from the return ducts formed by the channels 22, will maintain combustion upon the ash grate of any fuel which has not been burned in passing 80 down the grate bars.

To facilitate manufacture and to provide grate bars which are constructed for strength and lightness in weight, a particular construction is shown in the drawings, 90 but it will be understood that any suitable form of grate bars having longitudinal channels forming return ducts may be employed.

As particularly shown in Fig. 4, each grate bar comprises a central vertical longitudinal web 30 extending from the upper wall of the bar to the lower wall 27 thereof. This web gives rigidity to the bar to prevent sagging under load and extreme heat and the longitudinal passages 20 are formed by providing side plates 31 which are secured in any suitable manner to the bar to form the passages 20 between them and the central web, said plates being flanged inwardly at their lower 105 edges to meet ribs 32 extending laterally from the sides of the web 30 at a distance above the lower wall 27 of the bar. These flanges 32 together with the plates 31 form the dividing wall between the passages 20 110 and channels 22 and as the passages 20 are directly below the upper wall which forms the fuel surface of the grate, the cold air passing into the upper open ends of these passages from the wind box 2, effectively 115 cools the grate surface and prevents the grates from burning out. The streams of air passing through the several passages 20 become heated and pass out of the lower ends of these channels through the openings 21 into 120 the lower ends of the channels 22 at the lower sides of the bars. These ducts are in direct communication throughout their lengths with the slots 23 between the several bars so that this heated air is effectively distributed 125 by the several ducts over the entire grate and escapes through the slots 23, maintaining combustion upon the grate.

The entire volume of air for maintaining combustion is thus divided into a large num- 130

ber of streams, one for each slot 23, and thus the air is directed and forced to all parts of the grate evenly. The openings 26, which are intermittently opened by the movement 5 of the movable grate bars, supply just sufficient air to the chamber 29 beneath the ash grate, to maintain combustion upon the ash grate of any residue of fuel which may be carried down with the ash and clinker and 10 discharged upon said grate. The reciprocating movement of the movable grate bars imparts a similar movement to the ash grate to cause the ash and clinker to be finally discharged over the end of the ash grate into 15 the clean-out chamber 9 located in the side wall of the furnace where it may be readily removed without interrupting the operation of the furnace. The upper ends of all of the grate bars project into the hollow twyer 3 20 and as this twyer spans the space between the side of the wind box and the adjacent side of the retort, the air has a free flow into the open lower end of the twyer where it divides, part passing through the twyer 25 openings 33 and the remainder passing directly into the open ends of the grate bars, through the unobstructed passages 20, and return air ducts formed by the channels 22 from which it flows freely and is thereby 30 confined and directed to the slots between the several bars. The lower wall 27 of each bar being flanged and faced off along its edges to engage the edges of the lower walls of the adjacent bars, makes a tight joint between 35 the lower walls of the several bars and closed air ducts, each comprising two confronting channels 22 are thus formed between the bars, and the escape of air through the joints into the space or chamber 28 below the grate 40 bars is prevented.

Obviously the structure of the several grate bars may be changed to suit the conditions to which they may be put in use and they may be formed with one or more longitudinal passages 20 and with one or more of the channels 22 communicating therewith and with the discharge slots between the bars. It is also obvious that the volume of air passing out of the hollow grate bars may 45 be divided and directed by any suitable means to the several slots between the grate bars for maintaining combustion without the necessity for maintaining an air tight chamber beneath the grate and I do not, therefore, 50 limit myself to the particular construction of grate bars shown in the drawings. The invention may be applied to other forms or construction of furnaces in which stationary or movable or part stationary and part movable grate bars are used and the particular arrangement of stationary and movable grate bars and mechanism for operating the same 55 may also be varied without departing from the spirit of the invention. I do not therefore 60 fore limit myself to the form or arrangement 65

of furnace shown in the drawing which is illustrative of an application of my invention.

What I claim is:

1. In a furnace the combination of a plurality of grate bars each formed with a longitudinal passage adjacent the upper surface of the bar and open at one end of the bar to receive air under pressure, and also formed with a longitudinal channel below

70 said passage, said channel being in communication with said passage at the end of the bar opposite its open end, said channel being open through a side of the bar substantially throughout its length to discharge 75 the air laterally into the space between adjacent bars, said bars being formed to close the space between adjacent bars at the lower side of the grate.

2. In a furnace, a grate having a plurality of passages extending longitudinally thereof adjacent the upper surface of the grate and open at one end of the grate to receive air, said grate being also formed with air ducts extending longitudinally of the grate beneath said passages and in communication with said passages adjacent the end of the grate opposite that through which the passages open, said air ducts each opening 80 through the surface of the grate between 85 said first named passages and substantially throughout the length of the grate.

3. In a furnace the combination of a plurality of grate bars arranged side by side and in contact at the lower side of the grate to form an impervious wall at the lower side of the grate, said bars being also formed to provide longitudinal slots in the upper grate surface between the bars and each bar being formed with a longitudinal passage 100 opening through one end of the bar to receive air, and also formed with a longitudinal channel beneath said passage, which channel is in communication with said passage and opens into the space between adjacent bars to discharge air through the slots in the grate surface.

4. In a furnace, the combination of a plurality of grate bars formed to contact each other adjacent the lower side of the grate and form an impervious lower wall for the grate, said bars being also formed to provide longitudinal slots in the upper grate surface between the bars a plurality of longitudinally extending air passages and air ducts, said passages for conducting air throughout the length of the grate adjacent the upper surface thereof to cool said surface, and said ducts arranged to receive air from said passages and discharge the same 115 upwardly through said slots in the upper grate surface.

5. In a furnace, a grate comprising a plurality of hollow grate bars formed to closely contact each other at the lower side of the

grate and together form an impervious bottom wall for the grate, said bars being also formed to provide longitudinal slots in the upper grate surface between adjacent bars, 5 said hollow bars each being open at one end to receive air under pressure and formed to conduct the air to the opposite end of the bar, adjacent bars being formed to receive the air at the ends of the bars to which it is 10 conducted and discharge the same into and upwardly through the slots in the upper grate surface.

6. In a furnace, a grate comprising a plurality of grate bars each having an air inlet 15 passage open adjacent one end of the bar to receive air under pressure and having a channel beneath said air inlet passage, said channel communicating with the said passage at the end of the bar opposite that 20 through which the passage opens, said channel opening through a side of the bar and forming together with a channel in an adjacent bar, a passage which is open upwardly through the grate surface between 25 adjacent bars.

7. In a furnace, a grate comprising a plurality of fixed and movable hollow grate bars adapted to receive air and to discharge the same throughout the grate surface, said 30 movable bars having openings adapted to be opened intermittently by the movement of said bars to discharge air therefrom for maintaining combustion other than upon said grate surface.

35 8. In a furnace, a grate comprising a plurality of fixed and movable hollow grate bars adapted to receive air under pressure and to discharge the same directly through the grate surface for maintaining combustion 40 thereon, said movable grate bars being provided with outlet openings adapted to be opened and closed by the movement of said bars.

9. In a furnace, a grate comprising a plurality of fixed grate bars and movable grate bars, all of said bars being formed with inlet passages to be supplied with air under pressure, said bars being also formed to provide outlet ducts communicating with said 50 inlet passages, said outlet ducts being arranged to discharge directly through the grate surface substantially throughout the length of the grate, and each of said movable bars being provided with an outlet opening for one of said outlet ducts, said outlet openings being arranged to be opened and closed by the movements of said movable bars.

60 10. In a furnace, the combination with a twyer, and means for supplying air under pressure to said twyer, of a grate formed of a plurality of grate bars each having a plurality of separate longitudinal air passages open at one end into said twyer, and 65 also formed with a plurality of separate lon-

70 gitudinal channels below said passages opening through the sides of the bar and communicating with said passages at the end of the bar opposite the open end of the passages, the channels in adjacent bars together forming longitudinal air passages opening through the upper grate surface between the bars, said bars being in close contact at their lower sides to provide an impervious lower grate wall. 75

11. In a furnace, the combination with a hollow twyer and grate supports, of a plurality of grate bars supported upon said supports and together forming a grate, each bar being formed with a longitudinal air inlet passage opening through one end of the bar into the twyer, and with a return air outlet channel beneath the inlet passage communicating with the inlet passage at the opposite end of the bar, said return channel opening into the space between adjacent bars, said bars being in contact with each other adjacent the lower sides thereof to prevent the escape of air through the space between the bars into the space below the 80 grate. 85

12. In a furnace, the combination with a hollow twyer and means for supplying air under pressure to said twyer, of a plurality of fixed and movable inclined grate bars each formed with a longitudinal passage opening through the upper end of the bar into the twyer and with a longitudinal outlet channel adjacent the lower side of the bar communicating with the inlet passage adjacent the lower end of the bar, the outlet channel being open through a side of the bar into the space between adjacent bars to discharge upwardly therethrough throughout the length thereof between adjacent bars, said adjacent bars being in contact at their lower edges to prevent the escape of air from the outlet passage into the space below the grate. 100 105

13. In a furnace, the combination of a hollow twyer, means for supplying air under pressure to the twyer, a plurality of hollow inclined grate bars supported with their open ends in communication with the twyer, means adjacent the lower ends of said bars for moving certain of said bars longitudinally, a support for the upper ends of the movable bars upon which they are free to slide, said movable bars being formed with air outlet openings opened and closed 110 by the movement of said movable bars, and an ash grate at the lower ends of said bars connected to the movable bars to move therewith, said ash grate being supplied 115 by air for the maintenance of combustion thereon, from the discharge openings in the grate bars. 120 125

14. In a furnace, the combination of a wind box, a retort supported upon the wind box, a hollow twyer spanning the space be- 130

tween the side of the retort and the side of a grate connected at one end to the movable 10
the wind box, a plurality of inclined hollow bars and supported at its opposite end with-
grate bars supported at their upper ends by in said clean-out opening.
the wind box with said ends in open com-
munication with the twyer, a support for
the lower ends of said bars, means for mov-
ing certain of said bars, a wall adjacent the
lower ends of the bars and spaced there-
from, a clean out opening in said wall and

In testimony whereof I affix my signa-
ture in the presence of two witnesses.
